(57) **CLAIM**

The ornamental design for a rotary actuator, as substantially shown and described.

DESCRIPTION

FIG. 1 is a front perspective view showing a rotary actuator. FIG. 2 is a back perspective view showing the rotary actuator.

FIG. 3 is a front view of the rotary actuator.

FIG. 4 is a back view of the rotary actuator.

FIG. 5 is a left view of the rotary actuator.

FIG. 6 is a right view of the rotary actuator.

FIG. 7 is a top view of the rotary actuator; and,

FIG. 8 is a bottom view of the rotary actuator.

In all figures, the broken lines are included for the purpose of illustrating portions of the rotary actuator that form no part of the claimed design.
